(57) **CLAIM**

The ornamental design for a dual wide LED lights fixture, as shown and described.

DESCRIPTION

FIG. 1 is a top perspective view of dual wide LED lights fixture showing my new design;

FIG. 2 is a left view thereof;

FIG. 3 is a front view thereof;

FIG. 4 is a right view thereof;

FIG. 5 is a back view thereof;

FIG. 6 is a top view thereof;

FIG. 7 is a bottom view thereof; and,

FIG. 8 is a bottom perspective view thereof.

The broken lines shown in the drawings are for the purpose of illustrating portions of the light fixture that form no part of the claimed design.
